208,377

CONTAINER FOR XEROGRAPHIC TONER POWDER

John W. Wagner, Penfield, and James K. Dennis, Fairport, N.Y., assignors to Xerox Corporation, Rochester, N.Y., a corporation of New York

Filed July 1, 1965, Ser. No. 85,984

Term of patent 14 years

(Cl. D58—17)

FIG. 1

FIG. 2

FIG. 3

FIG. 4

FIG. 5

FIG. 1 is a front perspective view of a container for xerographic toner powder showing our new design;

FIG. 2 is an inverted front perspective view;

FIG. 3 is a front elevational view;

FIG. 4 is an end elevational view looking from the right of FIG. 3; and

FIG. 5 is an end elevational view looking from the left of FIG. 3.

The side opposite that seen in FIG. 3 is plain and unornamented and is a continuation of the surface seen just above and below the dispensing openings in FIG. 3.

We claim:

The ornamental design for a container for xerographic toner powder, as shown and described.
